Garrettson Smith & Henry Brown, of Philadelphia Pa.

Assignors to

Smith, Francis & Wells, of Springville, Pa.

Letters Patent No. 1610 - dated July 1-1862,

The schedule referred to in these Letters Patent and making part of the same.

To all whom it may concern;

Be it known that we, Garrettson Smith and Henry Brown, of Philadelphia, County of Philadelphia, State of Pennsylvania, have invented or produced a new and original design for the plates of a Cooking Stove termed the "Wabash"; and they do hereby declare the accompanying drawing with the following explanation of the same to form a full, clear and exact description of the said design.

On referring to the annexed drawing -

Fig. 1. represents one of the side plates of the stove.

Fig. 2. the front plate.

Fig. 3. the back plate - and

Fig. 4. one of the legs of the stove.

The side plate (Fig. 1.) is edged with a plain moulding, and has one large door A. and a panel B.

The large door is edged with a plain moulding in the space inclosed by which is a scroll and foliated ornament surrounding an oval

Des 16/10

panel containing an oval ornament which consists of a central box with radial corrugations.

The panel B is also edged with a plain moulding, the space within has ornaments of a character similar to those on the door A.

Below the latter is a tablet formed by a scroll ornament, and in this tablet are the names "Smith, Francis, and Wells" in raised letters. Above the door A and panel B, is an ornament consisting of a row of sprigs.

The front plate Fig. 2, has plain mouldings on its opposite vertical edges, and has two upper doors C and C, and two lower doors D and D, the two upper doors having plain beads on the edges, and within these beads simple scroll ornaments. The two lower doors have ornaments of a character similar to those of the large door A, and panel B of the side plate Fig. 1.

The end plate Fig. 3, has on its opposite vertical edges, plain mouldings, and on its face a panel formed by scroll and foliated ornaments in the centre of which is an oval ornament similar to that on the large door A. Fig. 1.

The ornamentation of the leg will be clearly understood on reference to Fig. 4.

We claim the ornamental Figures and Forms represented in and by the accompanying drawing the whole forming an ornamental design for the side, front, and back plates and the legs of a cooking stove.

In testimony whereof, we have signed our names to this specification in the presence of two subscribing witnesses.
